COMPENSATING TURNTABLE DRIVE

Emmor V. Schneider, Alliance, Ohio, assignor to
The Alliance Manufacturing Company, Alli-
ance, Ohio, a corporation of Ohio

Application February 17, 1941, Serial No. 379,227

4 Claims. (Cl. 74—206)

The invention relates to phonograph turntable drives of the friction type disclosed in my co-pending application Serial No. 294,938, filed September 14, 1939, and is more particularly concerned with a compensating drive so constructed and arranged that it will operate the turntable at a uniform speed throughout the entire recording or reproducing of a record.

Owing to a growing demand in recent years for a combination recording and reproducing phonograph for home use, there are now upon the market many relatively inexpensive phonographs of this general type, equipped with induction motors for economic reasons.

Such phonographs however, are not entirely satisfactory, due largely to the fact that these inexpensive motors do not have sufficient power to drive the turntable at a uniform speed from the start to the end of a record, especially in recording, and also because they will not drive the turntable as rapidly when recording as when reproducing a record.

It has been found that in recording upon this type of phonograph there is a differential of approximately eighteen inch ounces to six inch ounces between the start and the end of a record, resulting in noticeable variations in both the pitch and the tempo of recordings made upon such phonographs.

It has also been found that there is a difference of approximately four revolutions per minute between the recording and the reproducing of a record upon such phonographs.

Another objection to this type of phonograph is that the pulsations or vibrations of the motor are reproduced to a greater or less degree in the record.

The present invention has for its objects the provision of a compensating turntable drive for phonographs, which will overcome the above mentioned objections and produce a uniform speed in recording and reproducing of records, as well as minimize the reproduction in the record of the pulsations or vibrations of the motor.

Another object of the invention is the provision of a turntable drive in which the axis of the motor is substantially parallel to the plane of the turntable, and in which a countershaft is provided substantially parallel to the motor shaft, a friction wheel upon said shaft engaging a friction pulley upon the motor shaft, a second friction wheel being slidably mounted upon said shaft and frictionally engaging the turntable, means being provided for moving said second friction wheel toward and from the center of the turn-

table to compensate for variations in the drag or torque upon the turntable between the start and end of a recording, or between the recording and reproducing of a record.

5 Still another object of the invention is the provision of a turntable drive of this character in which the two friction wheels are connected together by means of a torsion spring through which the drive is effected, so that the pulsations or vibrations of the motor will not be reproduced in the recording or playing of a record.

A further object of the invention is to provide a turntable drive of the type referred to in which the slidable friction wheel is moved longitudinally upon the shaft by means of a screw thread or helical rib.

20 The above objects, together with others which will be apparent from the drawing and following description, may be attained in various ways by which a slidably mounted friction wheel is moved radially relative to the turntable to compensate for drag or torque upon the turntable, and for the purpose of illustration a preferred embodiment of the invention is shown in the 25 accompanying drawing, in which—

Figure 1 is a fragmentary top plan view of the improved compensating turntable drive;

Fig. 2, a vertical sectional view taken as on the line 2—2, Figure 1; and

Fig. 3, an enlarged sectional view through the two friction wheels and associated parts;

Similar numerals refer to similar parts throughout the several views.

In the form of the invention shown, a portion 30 of the usual platform of a phonograph cabinet is shown at 10 and the turntable 11 is rotatably mounted upon the spindle 12 carried by said platform.

The turntable may be provided with the usual 35 depending peripheral flange 13 although the same is not necessary for the particular friction drive used in this invention.

A motor mounting plate 14 may be supported upon the platform 10 as by one or more rubber 40 grommets 15 secured to the platform as by the screw 16 and washer 17, a spacer sleeve 18 or the equivalent being preferably located around the screw and interposed between the platform and the washer 17.

45 Depending arms 19 may be formed upon or attached to the motor mounting plate and located through the openings 20 and 21 in the platform 10.

The motor, indicated generally at 22, is suspended upon the arms 19 to which it may be 50 connected as by the screws 23 and the motor is

so positioned that the shaft 24 thereof is located substantially in a horizontal plane. A friction pulley 25 is fixed upon the motor shaft.

A bearing 26 is swedged or otherwise connected to one arm 19 of the motor mounting plate to form a bearing for the shaft 27 which is journaled in said bearing and held against accidental removal as by the flange 28 which may be in the form of a washer located around the reduced end portion 29 of the shaft and retained thereon as by the riveted head 30 formed upon the adjacent end of the shaft.

A friction wheel 31 is fixed upon the shaft 27 adjacent to the bearing 26 as by the pin 32 located through the hub 33 of the friction wheel 15 and through a suitable opening 34 in the shaft.

A tire 35 of rubber or the like is mounted upon the friction wheel 31 and frictionally engages the pulley 25 upon the motor shaft so that the friction wheel 31 and shaft 27 may be rotated by the 20 motor.

A second friction wheel 36 is mounted for longitudinal movement upon the shaft 27 and is provided with a friction tire 37 frictionally engaging the underside of the turntable 11.

This friction wheel may be threaded upon the shaft 27 in any well known manner and as shown the hub 38 of the friction wheel is provided with a spiral rib 39 engaging a similar groove 40 in the shaft 27.

Outward movement of the friction wheel 36 beyond the adjacent end of the shaft 27 may be prevented as by the washer 41 located in a peripheral groove 42 formed in this end portion of the shaft.

A torsion spring 43 is located around the shaft 27, one end thereof being connected to the hub 38 of the friction wheel 36 as indicated at 44 while the other end of the spring is connected to the hub 33 of the friction wheel 31, and to the shaft 27 as indicated at 45.

A skirt 46 may be formed upon the hub of the wheel 36 to surround the spring 43.

In the normal position of the parts, as shown in Figs. 2 and 3, the spring 43 holds the friction wheel 36 at the outer end of the shaft 27 so that the tire of said friction wheel contacts with the undersurface of the turntable 11 near the periphery thereof.

As the motor 22 is operated, the friction pulley 25 drives the friction wheel 31 and shaft 27, and through the spring 43 the friction wheel 36 is rotated, driving the turntable at proper speed.

In the operation of the phonograph, as the pressure of the needle upon the record, carried by the turntable, offers resistance to the rotation of the turntable, the spring 43 will be wound upon itself rotating the movable friction wheel 36 upon the shaft in a direction whereby the screw threads 39-40 cause the wheel 36 to move longitudinally on the shaft toward the center of the turntable, bringing the tire 37 of the wheel 36 into contact with the turntable at a point closer to the center thereof.

The device thus compensates for changes in drag or torque upon the turntable, providing for a smooth uniform rotation of the turntable throughout the entire recording or playing of a record.

It will also be seen that since the drive is through the torsion spring 43 pulsations or vibrations of the motor will be absorbed by the spring producing a smooth continuous rotation of the turntable.

I claim:

1. A transmission including a driving means, a driven disk, a shaft operatively connected to the driving means, the axis of said shaft being located in a plane parallel to the normal plane of the driven disk, a friction wheel longitudinally movable upon the shaft and frictionally engaging the adjacent side of the driven disk, and torsion spring and screw means connecting the friction wheel and the shaft for moving the friction wheel toward and from the center of the driven disk to compensate for variations in drag and resultant speed changes of the driven disk.

2. A transmission including a driving means, a driven disk, a shaft operatively connected to the driving means and located radially relative to the driven disk, a friction wheel longitudinally movable upon the shaft and frictionally engaging the adjacent side of the driven disk, and torsion spring and screw means connecting the friction wheel and the shaft for moving the friction wheel radially upon the driven disk to compensate for variations in drag and resultant speed changes of the driven disk.

3. A transmission including a driving means, a driven disk, a shaft operatively connected to the driving means and located radially relative to the driven disk, a friction wheel threaded upon the shaft and frictionally engaging the adjacent side of the driven disk, stop means upon the shaft for limiting the movement of the friction wheel in one direction, and a torsion spring connected to the friction wheel and to the shaft for urging the friction wheel toward the stop means, so that the friction wheel is moved radially relative to the driven disk by variations in drag to compensate for resultant variations in speed of the driven disk.

4. A transmission including a driving means, a driven disk, a shaft operatively connected to the driving means and having a spiral groove therein, said shaft being located radially relative to the driven disk, a friction wheel longitudinally movable upon the shaft and having an internal, spiral rib received in said spiral groove, said friction wheel frictionally engaging the adjacent side of the driven disk, and a torsion spring connected to the friction wheel and to the shaft for moving the friction wheel radially upon the driven disk to compensate for variations in drag and resultant speed changes of the driven disk.

EMMOR V. SCHNEIDER.
